QUASI-IMPEDANCE RELAY SYSTEM

Shirley L. Goldsborough, Basking Ridge, N. J., assignor to Westinghouse Electric Corporation, East Pittsburgh, Pa., a corporation of Pennsylvania

Application November 29, 1947, Serial No. 788,910

10 Claims. (Cl. 175—294)

1

My invention has relation to a single quasi-impedance fault-detector, or pair of detectors, which is capable of taking the place of a plurality of phase- and ground-relays for responding to all kinds and combinations of faults on any of the different phases of a polyphase transmission-line. My invention also has more special relation to a phase-comparison, carrier-current, protective relaying-system utilizing a pair of my new fault-detectors having diverse sensitivities.

For some years, commercial use has been made of a phase-comparing carrier-current transmission-line protective-system, the latest form of which is described and claimed in an application, Serial No. 758,200, of H. W. Lensner et al., filed June 30, 1947. In this protective system, a first overcurrent relay, of a low current-setting, was used as a fault-detector for supervising all operations affecting the phase-comparison function, and a second overcurrent relay, having a higher current-setting, was used as a less sensitive fault-detector for supervising the tripping function. This type of carrier-current protective system is not of universal applicability, because, on a two-terminal line, the more sensitive fault-detector must be set to pick up at not less than 125% of the maximum three-phase load-current, and on a three-terminal line, the pick-up value must be increased to 250% of the load-current. Many applications for this relaying system have arisen, in which the minimum fault-current has been close to, or below, these values, thus limiting the application of the relay. The difficulty just mentioned could be avoided, of course, by using standard impedance-elements, but such a course would require one relay for each phase, for both phase- and ground-faults, and this would upset the inherent simplicity of the carrier-current protective system utilizing only a single fault-detector for taking care of all kinds and severities of phase- and ground-faults.

An object of my present invention is to provide a quasi-impedance relay which will respond to all kinds of faults, as by having an operating-coil which is energized from a phase-sequence line-current network which supplies a single quantity which is fairly uniformly responsive to all kinds and phases of faults, and having a restraint-coil which is energized from a minimum-voltage network, such as that which is shown in the Harder Patent 2,393,043 granted January 15, 1946.

A further object of my invention is to provide a phase-comparison carrier-current relaying-system, using one or two of the quasi-impedance

2

relays just described, thus overcoming the limitation as to the minimum permissible current-setting, without requiring any additional mechanical elements in the relay-assembly.

With the foregoing and other objects in view, my invention consists in the systems, circuits, combinations, elements and methods of design and operation, which are hereinafter described and claimed, and illustrated in the accompanying drawing, the single figure of which is a much simplified diagrammatic view of circuits and apparatus illustrative of my invention in a preferred form of embodiment.

In the drawing, I have illustrated my invention as applied to one terminal of a line-section 1 of a 3-phase transmission-line, which is connected to a 3-phase station-bus 2 by means of a circuit breaker 3 having a trip-coil TC and an auxiliary make-contact 3a. I have shown only one terminal of the protected line-section 1, with the understanding that the other terminal is, or may be, a duplicate of the terminal equipment which is illustrated.

I use a bank of line-current transformers 4, which respond to the 3-phase line-current in the protected line-section 1, and I supply this current to any suitable alternating-current transforming-device, network or filter, which is marked HCB, for deriving a single-phase alternating-current voltage which is applied to the primary winding of a non-saturable transformer NST. Any suitable network may be utilized, such as the network HCB as shown in the Harder Patent 2,183,646 of December 19, 1939, for deriving a single-phase relaying current or voltage which is reasonably uniformly responsive to a plurality of kinds and severities of phase- and ground-faults, on whatever line-phase a fault may occur. In my present invention, it is necessary or desirable, as will subsequently be explained, to use a non-saturating network-transformer NST, or none at all, instead of the saturating transformer advocated by Harder.

The secondary winding 5 of the non-saturating transformer NST is utilized to control two mechanical fault-detector relays FD1 and FD2, and also to control two alternately triggering gas-filled tubes V1 and V2.

In accordance with my present invention, the two fault-detector relays FD1 and FD2 are quasi-impedance relays having diverse sensitivities. Preferably, these relays are polarized relays. In the particular form shown, each relay has one operating-coil or winding, and one restraint-coil or winding, the operating-coil being designated

by the same designation as the relay as a whole, namely FD₁ and FD₂, respectively, whereas the restraint-coils have a subscript R appended thereto, thus FD_{1R} and FD_{2R}. Each of these relays is adjusted so that the relay will respond when the ampere-turns in its operating-coil just exceeds the ampere-turns in its restraint-coil.

The first fault-detector FD₁ is the more sensitive of the two relays, having a lower current-setting, and a higher impedance-response, so that it is the farther-reaching of the two.

The operating-coils of the two fault-detector relays FD₁ and FD₂ are energized in a manner which has been customary. They are shown as being energized in series with each other, from the output-terminals of a rectifier-bridge RB, which is supplied with energy from the secondary winding 5 of the non-saturating network-transformer NST. There are a number of different alternating-current transforming-devices or networks which are available, for providing suitable current for energizing the operating-coils FD₁ and FD₂ so that these relays will be fairly uniformly responsive to all kinds of phase- and ground-faults, no matter which phase, or how many phases, are affected.

In accordance with my invention, the fault-detector restraint-coils FD_{1R} and FD_{2R} are energized, preferably in series with each other, in such manner as to be responsive to a minimum-voltage network, such as that which was disclosed in the previously mentioned Harder Patent No. 2,393,043, so that the relay-restraint is selectively responsive to the minimum one of a selected number of line-voltages involving different line-phases. In the particular form of embodiment which I have chosen for illustration in the drawing, I use a minimum-voltage network which responds to the smallest of the three phase-to-phase line-voltages, as supplied by three potential-transformers T_a, T_b and T_c, but I am not limited to the phase-to-phase voltages. These potential-transformers energize three rectifier-bridges B_a, B_b and B_c, which in turn energize three capacitors C_a, C_b and C_c, each of which is paralleled by a separate resistor R_r. The voltage-drops in the three network-resistors R_r are applied, in three parallel circuits, across the output-terminals m and n, through three reversely connected rectifiers 6_a, 6_b and 6_c, respectively. The reverse-current or leakage-current through the rectifiers is sufficient to keep the output-terminals m and n energized, while the forward-current conductivity of the rectifiers 6_a, 6_b and 6_c is sufficient to pull down the uni-directional output-terminal voltage to the same value as the lowest of the three rectified line-voltages.

Since the minimum-voltage network just described has a fairly wide range of voltage-response, provided that no appreciable energy is taken from the output-conductors m and n, I use a very high loading-resistance R_{O1}, which is connected across the output-terminals m and n of the minimum-voltage network, this loading-resistance being preferably comparable to, or larger than, the effective reverse-current resistance of any one of the network-rectifiers 6_a, 6_b or 6_c. A suitable portion of the network-voltage is tapped off of the loading-resistance R_{O1}, as shown at 7, and applied to the grid-control circuit of a triode tube 9, which has the two restraint-coils FD_{1R} and FD_{2R} connected in series with its plate-circuit, the plate-voltage being supplied by a resistor R_{O2}, which serves as a potentiometer energized

from a battery 10, or any other suitable direct-current source.

The circuits of the several relays which are used in my invention are arranged, as far as practicable, after the manner of a schematic diagram or "across-the-line" diagram. In each case, the main or operating coil of the relay is given a letter-designation or legend, and the same letter-designation or legend is applied to all of the contacts of that relay. The relays and switches are invariably shown in their open or deenergized positions. Arrows are used to symbolically indicate how the various parts of each relay are connected together.

As shown in the Lensner et al. application, the gas-filled tubes V₁ and V₂ are controlled from the secondary winding 5 of the non-saturating transformer NST, by having the tube-grids G₁ and G₂ energized, through resistors R₁ and R₂, from two secondary windings 11 and 12 of an input-transformer IT, the primary of which is energized from the secondary winding 5 of the non-saturating transformer NST. The other two terminals of the secondary windings 11 and 12 of the input-transformer IT are shown as being connected together, in a circuit 14 which is connected to an intermediate tapped-point of a cathode-circuit biasing-resistor R₃, which is in the cathode-circuits of the gas-tubes V₁ and V₂.

As shown in the drawing, one terminal of the cathode-circuit biasing-resistor R₃ is connected to the negative bus (—) of a direct-current voltage-source for the tubes, while the other terminal of said resistor is connected to a conductor 15, which is utilized for several purposes. The circuit 15 is utilized to energize one terminal of a cathode-circuit loading resistor R₄, the other terminal of which is connected to the cathode-terminal 21 of the first, or carrier-starting, gas-tube V₁. The circuit 15 is also utilized to energize one terminal of another cathode-circuit loading-resistor R₅, the other terminal of which is connected to the cathode-circuit 22 of the second, or relay-energizing, gas-tube V₂.

The two grid-terminals of these tubes V₁ and V₂ are connected to their respective cathode-circuits 21 and 22 through capacitors C₁ and C₂, as is known in the art. The two plate-circuits P₁ and P₂ of these two tubes are connected together through a capacitor C₃ which assists in firing-transfer. The two cathode-circuit loading-resistors R₄ and R₅, respectively, are shunted by capacitors C₄ and C₅, which also assist in firing-transfer. The circuit 14, which is connected to an intermediate tap of the cathode-circuit biasing-resistor R₃, is also connected to the circuits of the screen grids SG₁ and SG₂ of the respective gas-tubes V₁ and V₂. The two plate or anode-circuits P₁ and P₂ of the two gas-tubes are connected, respectively, through resistors R₆ and R₇, to a common conductor 24, which is in turn connected to the positive bus (+) through a resistor R₈.

The two alternately firing gas-tubes V₁ and V₂ are supervised by the high-impedance or far-reaching fault-detector FD₁, by having the positive tube-circuit 24 connected to the negative terminal (—) through the normally closed back-contact 25 of said high-impedance fault-detector FD₁.

The back-contact 25 of the high-impedance fault-detector FD₁ is also utilized to control the energization of an auxiliary relay K, by having the operating-coil K of this auxiliary relay connected, through a resistor R₉, across the FD₁

back-contact. The auxiliary relay K has a single back-contact K, which is connected in series with a telemetering key TM, which is indicated by way of illustration of carrier-current control for purposes other than relaying. The auxiliary-relay back-contact K thus acts substantially like a back-contact placed upon the high-impedance fault-detector FD1, said auxiliary relay K being utilized for supplying this contact in order to avoid mechanically overloading the low-energy fault-detector FD1.

The cathode-circuits 21 and 22 of the respective gas-filled tubes V1 and V2 are utilized as sources of two alternating series of square-topped positive-voltage impulses, for two different purposes. These positive-voltage impulses, are the voltage-drops through the respective cathode-circuit loading-resistors R4 and R5, which have voltage-drops therein when their respective tubes V1 and V2 are firing.

The cathode-circuit 21 of the first gas tube V1 is utilized to energize the plate-circuit P3 of a carrier-current master-oscillator tube OSC, through a radio frequency choke-coil RFC-1. This oscillator-tube OSC serves as a carrier-current transmitter for transmitting a succession of bursts of substantially square-topped, or unmodulated, carrier-frequency impulses to the other line-section terminal (not shown), as will be subsequently described. During fault-free conditions of the transmission-system, the gas-tubes V1 and V2 are not firing, because of the short-circuiting back-contact FD1, and at such times the carrier-current oscillator OSC may be energized through the telemetering key TM, and the back-contact K, which connect the circuit 21 to the positive bus (+) through a resistor R-10.

The transmitter-oscillator OSC has its screen-grid SG3 connected to the plate-supply circuit 21 of said oscillator. The cathode-circuit of the oscillator OSC is the previously-mentioned circuit or conductor 15. The oscillator has a grid-circuit G3, which is connected to the cathode-circuit 15 through a grid-resistor R-11.

The plate-circuit P3 of the oscillator OSC is connected, through a blocking-capacitor BC1, to an intermediate terminal 27 of a tuned carrier-frequency circuit, comprising the conductor 27, a capacitor C6, a conductor 28, a capacitor C7, the cathode-circuit 15, a capacitor C8, the grid-circuit G3, and a variometer L1, the other terminal of which is connected to the starting-point 27 of the tuned circuit.

The conductors 28 and G3 of this tuned circuit are respectively utilized to apply radio- or carrier-frequency control-voltages, through blocking-capacitors BC2 and BC3, respectively, to the grids of two amplifier-tubes A1 and A2. The cathodes of the amplifiers A1 and A2 are connected to the cathode circuit 15 of the oscillator OSC. The grids of the amplifier-tubes A1 and A2 are connected, through grid-resistors GR1 and GR2, to the negative bus (-), so as to apply a negative bias equal to the drop across the cathode-circuit biasing-resistor R3. The two plates of the amplifiers A1 and A2 are connected to the primary-winding terminals of a radio-frequency output-transformer OT. The primary winding of said output-transformer OT has a midpoint tap 30 which is connected to the positive supply-terminal (+) and also to the screen-grids of the two amplifiers A1 and A2.

The radio-frequency output-transformer OT has a secondary winding 31, having one of its terminals grounded, and having two taps 32 and

33. The output-transformer secondary-tap 32 is connected to phase-C of the line 1, through a variometer L2, a conductor 34, and a coupler-capacitor CC. The conductor 34 is also grounded through a grounding-coil GC. The secondary tap 33 of the radio-frequency output-transformer OT is utilized to energize the primary winding of a receiver-coupling transformer RCT, through a tuning-capacitor T-C. The primary winding of the receiver-coupling transformer RCT is also preferably protected by a shunt-connected voltage-limiting gas-filled tube GT.

The receiving-coupler transformer RCT has a secondary winding 36 which is part of a tuned receiving-circuit, comprising said secondary winding 36, the grid-conductor G4 of a receiver-tube REC, a tuning-capacitor C9, the circuit or conductor 15, and thence back to the secondary winding 36.

The receiver-tube REC is a saturating-tube which carries a plate-cathode current which is of a substantially constant magnitude, whenever the tube is conducting at all, substantially regardless of the voltage applied to the grid-circuit G4, provided that this grid-voltage is high enough to cause plate-current to flow.

The receiver-tube REC has its cathode-circuit 37 energized from a tapped point of a potentiometer PO4 which is connected between the circuit 15 and the positive bus (+). The receiver-tube REC has a plate circuit P4, which is energized from the positive supply-terminal (+) through a radio-frequency choke-coil RFC-2. In the drawing illustrative of my invention, I have symbolically shown the telemetering relays 38 in series with the plate-circuit P4, although it should be understood that, in general, the telemetering relays 38 would be utilized only at one line-terminal, while the telemetering key TM would be utilized at the other line-terminal. The receiver-relay REC also has a screen-grid circuit SG4 which is connected to the positive terminal (+).

The receiver-relay plate-circuit P4 is utilized to apply a restraining voltage to the grid-circuit G5 of a relay-tube RT, through a coupling-capacitor C-10, a conductor 39, a voltage-doubler which is generically indicated at 40, and a grid-circuit resistor R-12. The voltage-doubler 40 consists of a resistor R-13, which is connected between the conductor 39 and the cathode-circuit 22 of the second gas tube V2, a capacitor C11, which is connected between the circuit 39 and a circuit 41, a double-circuit rectifier-valve RV, and a loading-resistor R-14. The loading-resistor R-14 is connected between the cathode-circuit 22 of the gas tube V2 and the anode-circuit 42 of the right-hand rectifier of the rectifier-valve RV. The circuit 42 also constitutes the input-terminal of the grid-circuit resistor R-12 of the receiver-tube RT. The cathode of the right-hand half of the double-rectifier valve RV is connected to the conductor 41, while the anode of the left-hand rectifier-circuit of the doubler valve RV is connected to this same conductor. The cathode of the left-hand rectifier of the double valve RV is connected, at 43, to the cathode-circuit 22 of the second gas valve V2. The loading-resistor R-14 is bypassed by a ripple-smoothing radio-frequency bypass-capacitor BPC.

The relay-tube RT has its cathode-circuit 44 energized from a tapped point of a potentiometer PO5 which is connected between the conductor 15 and the positive supply-terminal (+). The plate-circuit P5 of the relay-tube RT is connected through the primary winding of a relay output-

transformer ROT, a conductor 45, a make-contact 46 of the low-impedance fault-detector FD2, and thence to the positive terminal (+). The screen-grid circuit SG5 of the relay-tube RT is also connected to the aforesaid conductor 45.

The relay output-transformer ROT has a secondary winding 47, which is used to energize the operating-coil R of a relay R, which has a single make-contact 48, which is shown, near the top of the negative supply-terminal (-), as being in the tripping-circuit of the trip-coil TC of the circuit breaker 3, this trip-circuit extending from the negative bus (-) to the positive bus (+), and also including the auxiliary breaker-contact 3a.

In operation, it will be observed that my differential fault-detectors FD1 and FD2 have a distance-response which is not a measure of the true impedance of the fault, yielding a sort of quasi-impedance response. This is true, because the operating-coil which is supplied by the current-network HCB is slightly different, for faults on different phase-conductors, and also for single ground-faults, double ground-faults, ungrounded 2-phase faults, and 3-phase faults.

It is to be noted, however, that the balance-points of both fault-detectors FD1 and FD2 both shift at the same time and in the same direction, according to the particular type of fault and the particular phase which is affected by the fault. Since the two balance-points of the two fault-detectors both shift in the same direction, whenever the distance-setting of the relays change, there will always be maintained a predetermined margin between the two distance-responses. In many applications of fault-detectors, and especially in the particular fault-detector application which I have illustrated, in connection with a phase-comparing carrier-current protective system, the precise balance-point of a fault-detector is unimportant, because other means are provided for determining which fault to respond to, by way of a tripping-operation, but it is quite important that the relative sensitivities of two fault-detectors should be reliably maintained to all conditions. This function is admirably accomplished by my fault-detectors, because both detectors have a relay-restraint which is proportional to the minimum line-voltage, i. e., the line-voltage which has suffered the greatest voltage-drop under fault-conditions.

In some phase-sequence current-networks, such as the schematically indicated network HCB in my drawing, the network is more or less heavily weighted in response to the zero-sequence line-current component, so as to increase the sensitivity of responsiveness of the network to ground-faults, as compared to phase-faults, because ground-faults commonly involve smaller fault-currents than phase-faults. This over-sensitive current-response to ground-faults is particularly useful, when used in combination with a minimum-voltage network which responds to phase-to-phase voltages, as distinguished from phase-to-ground voltages. Because of the phase-to-phase minimum-voltage-response, the particular minimum-voltage network which is illustrated in the drawing applies a high restraint-voltage to the differential relays or quasi-impedance detectors FD1 and FD2, in the case of phase-to-ground faults, because normally a phase-to-ground voltage should be applied to a ground-fault impedance-relay. Since, however, my relay FD1 or FD2, in responding to ground-faults, has too high a current and too high a voltage

applied thereto, these two discrepancies tend to cancel each other, causing the distance-response or "reach" of the relays FD1 and FD2 to be more nearly the same for phase-faults and ground-faults.

The operation of the carrier-current part of the illustrated application of my invention will now be described. When a fault of a predetermined severity occurs on the protected line-section 1, one or both of the two fault-detectors FD1 and FD2 will pick up. The high-impedance detector FD1 is the more sensitive of the two, and when it responds, it opens its back-contact 25, and thus removes a short-circuit from around the two gas tubes V1 and V2. The grid-circuit setting of these gas-tubes V1 and V2 is such that said tubes are already in readiness to fire, in response to the alternating voltages which are applied to their respective grids G1 and G2.

Whichever one of the two gas tubes V1 and V2 has a positive grid voltage applied to it, at the moment of opening of the FD1 back-contact 25, will instantly begin firing, developing a certain positive voltage in its cathode-circuit 21 or 22, as the case may be, making said cathode-circuit positive with respect to the conductor 15. During the next half-cycle of the line-current, or output of the secondary winding 6 of the non-saturating transformer NST, a positive grid-voltage is applied to the other one of the two gas-tubes V1 and V2, causing this other tube to fire, putting out the first-firing gas-tube, in the process. The two gas-tubes V1 and V2 thus operate as sources of two different series of flat-topped voltage-waves of constant magnitude, one gas tube being responsive to positive line-frequency half-cycles, while the other is responsive to negative line-frequency half-cycles.

Carrier-current is transmitted by the firing of the master-oscillator OSC during the flat-topped voltage-impulses which are supplied from the cathode-circuit 21 of the first gas-tube V1, thus transmitting a succession of bursts of carrier-current energy, which are applied to the line through the coupling capacitors CC, during line-current half-cycles of one polarity. During the line-current half-cycles of the other polarity, a positive or operating-voltage is applied to the grid-circuit G5 of the relay-tube RT through the cathode-circuit 22 of the second gas-tube V2, the voltage of the circuit 22 being applied to the grid-circuit G5 in series with the resistor R-14, the conductor 42, and the resistor R-12. This operating-voltage tends to cause the flow of plate-current in the relay-tube RT.

The carrier-current impulses which are transmitted from both ends of the protected line-section are received in the receiver-tube REC at each end of the line-section, but the only important received carrier-impulses, at either end, are those which are received from the far end of the protected line-section, because the carrier-current impulses, or bursts, or operating-periods, which are transmitted from the relaying station itself, always occur during the half-cycles of the line-current when no operating-voltage is applied to the grid-circuit G5 of the relay-tube RT from the cathode-circuit 22 of the second gas tube V2.

At the far end of the protected line-section, however, the carrier-current energy-impulses or bursts, which are transmitted at line-frequency half-cycle intervals, are transmitted in response to the cathode-circuit 21 of the first gas tube V1 in that station, so that, if the in-looking line-current at the far-end station is 180° out of phase

with the line-current at the relaying station (as it will be, when there is no fault in the protected line section), then the carrier-current transmitting-periods at the far end will exactly coincide with the operating-voltage half-cycle periods at the relaying station, and thus they will block a response of the relay-tube RT.

The received carrier-current energy is applied, in a blocking fashion, to the grid-circuit G5 of the relay tube RT, through the coupling capacitor C-10 and the voltage-doubler 49, which operates to build up a negative voltage, in the loading resistor R-14, which is at least as large as, and opposite in sign to, the positive grid-voltage which is supplied by the cathode-circuit 22 of the second gas tube V2.

The result of the foregoing operations is that the relay-tube RT will become conducting only when there is an internal fault, or a fault within the protected line-section 1, in which case the tube will become conducting periodically, in short or long bursts, depending upon the phase-relations between the line-currents at the opposite ends of the protected line-section. The alternating-current component of the plate-current of the relay-tube RT is applied to the operating coil of the phase-angle-responsive relay R, through the relay output-transformer ROT. The contact 48 of the relay R is then utilized to trip the breaker 3.

It will be noted that the carrier-current equipment acts as a pilot-channel connecting the two ends of the protected line-section for the purpose of effecting a determination or comparison of the phase-angle between the two terminal line-currents of the protected line-section.

In order to insure the proper operation of the relay R, in view of its dependence upon fault-responsive relay-operations at two widely-separated points, namely at the two opposite ends of the protected line-section, it is necessary to make sure that the restraining impulses which are applied to the relay-tube RT are applied at least as soon as, and usually a trifle ahead of, the effective application of the operating-impulses to the grid-circuit G5 of this relay-tube RT. This coordination is obtained by using the second mechanical fault-detector FD2 to supervise the tripping-circuit relay R, in response to the same derived fault-current which is utilized to energize the first fault-detector FD1; but the second fault-detector FD2 has a slightly higher current-setting, or lower impedance-setting, such as responding to a current-value of approximately 125% of the pick-up setting of the first fault-detector FD1, or an apparent impedance-value of approximately 80% (or any other fraction) of the pick-up setting of the first fault-detector FD1.

In the illustrated embodiment of my invention, I also make use of a back-contact 25 (rather than a make-contact), on the first, or sensitive, fault-detector FD1, because a back-contact will not bounce, in response to a fault, thus avoiding the possibility of a momentary interruption of the transmission of a blocking or restraining signal at the beginning of a fault, thus resulting in false tripping at the opposite terminal. I also use a make-contact, 46, on the second fault-detector FD2, so that, even though both of the fault-detectors should pick up simultaneously, the detector having the back-contact will get that contact open before the other detector has moved far enough to close a normally open make-contact, thus insuring that a restraining-voltage is available, on the relay-tube RT, a trifle

ahead of the effective application of an operating-voltage to the grid-circuit G5 of said relay tube RT. It will be understood, of course, that no grid-circuit voltage is effective, on any tube, unless a suitable plate-voltage is being applied to the tube, so that the blocking of the operating voltage of the tube can be effected either by preventing the application of a sufficiently positive grid-voltage to the tube, or by preventing the application of a sufficient plate-voltage to the tube.

While I have illustrated my invention, and described its application, in but a single form of embodiment, which has been chosen for illustrative purposes, I wish it to be understood that many changes of addition, substitution or deletion could be made, without departing from the essential spirit of my invention. I desire, therefore, that the appended claims shall be accorded the broadest construction consistent with their language.

I claim as my invention:

1. Terminal equipment for one terminal of a pilot-channel phase-angle relaying-system for a polyphase line, comprising the combination, with a relay to be controlled, and a pilot-channel means for communicating with another terminal of the protected line-section, of means for deriving a single electrical current-responsive quantity from the polyphase line-current in such manner that the derived current-responsive quantity is responsive to a plurality of different kinds and severities of phase- and ground-fault conditions, means for deriving a single electrical voltage-responsive quantity from the several line-voltages in such manner that the derived voltage-responsive quantity is selectively responsive to the line-voltage having the greatest voltage-drop under fault-conditions, quasi-impedance fault-detector means, means for differentially energizing said fault-detector means from said two derived quantities, line-current-responsive impulse-producing means, operating under the supervision of said fault-detector means, for applying a succession of operating-impulses, effective on said relay, in response to derived line-current half-cycles of one polarity, and for delivering a succession of pilot-channel-controlling impulses to said pilot-channel means in response to derived line-current half-cycles of the opposite polarity, receiving-means for applying restraining-impulses, effective on said relay, in response to pilot-channel impulses received from another terminal of the protected line-section, and means for supervising said relay in response to said fault detector means.

2. The invention as defined in claim 1, characterized by said operating-impulses, said pilot-channel-controlling impulses, and said restraining-impulses all being substantially flat-topped impulses of substantially constant magnitudes which are substantially independent of the fault-severity, the magnitude of the derived line-current or the magnitude of the received energy which is received over said pilot-channel.

3. Terminal equipment for one terminal of a pilot-channel phase-angle relaying-system for a polyphase line, comprising the combination, with a relay to be controlled, and a pilot-channel means for communicating with another terminal of the protected line-section, of an alternating-current means for deriving a single-phase electrical current-responsive quantity from the polyphase line-current in such manner that the derived current-responsive quantity is responsive

to a plurality of different kinds and severities of phase- and ground-fault conditions, a means including a rectifier for deriving a unidirectional current-responsive quantity from said single-phase quantity, a minimum-voltage means, including rectifiers, for deriving a selected unidirectional voltage-responsive quantity from the several line-voltages in such manner that the selected quantity is responsive to the line-voltage having the greatest voltage-drop under fault-conditions, quasi-impedance, polarized fault-detector means, means for differentially energizing said fault-detector means from said two derived unidirectional quantities, line-current-responsive impulse-producing means, operating under the supervision of said fault-detector means, for applying a succession of operating-impulses, effective on said relay, in response to derived alternating-current half-cycles of one polarity, and for delivering a succession of pilot-channel-controlling impulses to said pilot-channel means in response to derived alternating-current half-cycles of the opposite polarity, receiving means for applying restraining-impulses, effective on said relay, in response to pilot-channel impulses received from another terminal of the protected line-section, and means for supervising said relay in response to said fault-detector means.

4. The invention as defined in claim 3, characterized by said operating-impulses, said pilot-channel-controlling impulses, and said restraining-impulses all being substantially flat-topped impulses of substantially constant magnitudes which are substantially independent of the fault-severity, the magnitude of the derived line-current, or the magnitude of the received energy which is received over said pilot-channel.

5. Terminal equipment for one terminal of a pilot-channel phase-angle relaying-system for a polyphase line, comprising the combination, with a relay to be controlled, and a pilot-channel means for communicating with another terminal of the protected line-section, of means for deriving a single electrical current-responsive quantity from the polyphase line-current in such manner that the derived current-responsive quantity is responsive to a plurality of different kinds and severities of phase- and ground-fault conditions, means for deriving a single electrical voltage-responsive quantity from the several line-voltages in such manner that the derived voltage-responsive quantity is selectively responsive to the line-voltage having the greatest voltage-drop under fault conditions, two quasi-impedance fault detector means having diverse sensitivities, means for differentially energizing both of said fault-detector means from said two desired quantities, line - current - responsive impulse - producing means, operating under the supervision of the far-reaching fault-detector means, for applying a succession of operating-impulses, effective on said relay, in response to derived line-current half-cycles of one polarity, and for delivering a succession of pilot-channel-controlling impulses to said pilot-channel means in response to derived line-current half-cycles of the opposite polarity, receiving means for applying restraining-impulses, effective on said relay, in response to pilot-channel impulses received from another terminal of the protected line-section, and means for supervising said relay in response to the nearer-reaching fault-detector means.

6. The invention as defined in claim 5, characterized by said operating-impulses, said pilot-

channel-controlling impulses, and said restraining-impulses all being substantially flat-topped impulses of substantially constant magnitudes which are substantially independent of the fault-severity, the magnitude of the derived line-current, or the magnitude of the received energy which is received over said pilot-channel.

7. The invention as defined in claim 6, characterized by the two fault-detector means being similarly operating mechanical relays, the more sensitive fault-detector relay having a normally closed contact, which opens when the relay responds to a fault, and the less sensitive fault-detector relay having a normally open contact, which closes when the relay responds to a fault, the fault-detector supervision which is specified in claim 9 being effected by said contacts, respectively.

8. Terminal equipment for one terminal of a pilot-channel phase-angle relaying-system for a polyphase line, comprising the combination, with a relay to be controlled, and a pilot-channel means for communicating with another terminal of the protected line-section, of an alternating-current means for deriving a single-phase electrical current-responsive quantity from the polyphase line-current in such manner that the derived current-responsive quantity is responsive to a plurality of different kinds and severities of

phase- and ground-fault conditions, a means including a rectifier for deriving a unidirectional current-responsive quantity from said single-phase quantity, a minimum-voltage means, including rectifiers, for deriving a selected unidirectional voltage-responsive quantity from the several line-voltages in such manner that the selected quantity is responsive to the line-voltage having the greatest voltage-drop under fault-conditions, two quasi - impedance, polarized,

fault-detector means having diverse sensitivities, means for differentially energizing both of said fault-detector means from said two derived unidirectional quantities, line-current-responsive impulse-producing means, operating under the supervision of the far-reaching fault-detector means, for applying a succession of operating-impulses, effective on said relay, in response to derived alternating-current half-cycles of one polarity, and for delivering a succession of pilot-

channel-controlling impulses to said pilot-channel means in response to derived alternating-current half-cycles of the opposite polarity, receiving means for applying restraining-impulses, effective on said relay, in response to pilot-channel impulses received from another terminal of the protected line-section, and means for supervising said relay in response to the nearer-reaching fault-detector means.

9. The invention as defined in claim 8, characterized by said operating-impulses, said pilot-channel-controlling impulses, and said restraining-impulses all being substantially flat-topped impulses of substantially constant magnitudes which are substantially independent of the fault-severity, the magnitude of the derived line-current, or the magnitude of the received energy which is received over said pilot-channel.

10. The invention as defined in claim 8, characterized by the two fault-detector means being similarly operating mechanical relays, the more sensitive fault-detector relay having a normally closed contact, which opens when the relay responds to a fault, and the less sensitive fault-detector relay having a normally open contact,

which closes when the relay responds to a fault, the fault-detector supervision which is specified in claim 8 being effected by said contacts, respectively.

SHIRLEY L. GOLDSBOROUGH.
